UNITED STATES PATENT OFFICE.

JOSEPH F. VAILLANCOURT, OF FALL RIVER, MASSACHUSETTS.

PICKER-STICK LUG-STRAP.

1,193,847.

Specification of Letters Patent.

Patented Aug. 8, 1916.

Application filed January 21, 1916. Serial No. 73,369.

To all whom it may concern:

Be it known that I, JOSEPH F. VAILLANCOURT, a citizen of the United States, residing at Fall River, in the county of Bristol 5 and State of Massachusetts, have invented certain new and useful Improvements in Picker-Stick Lug-Straps, of which the following is a specification.

This invention relates to improvements in 10 looms, and relates more particularly to a picker stick lug strap, one object of the invention being the provision of a lug strap, which is provided with removable or detachable wearing parts, so that such parts 15 may be removed and renewed, and thus not necessitate the discarding of the complete lug strap, as is the common practice.

A further object of this invention is the 20 provision of a lug strap which is provided with removable connections for receiving the picker stick and the rocking member for imparting movement to the picker stick thereby rendering it possible to renew either 25 connection without discarding the complete strap.

A still further object of the present invention is the provision of a simple, durable and inexpensive picker stick lug strap, which is thoroughly efficient and practical in use 30 and operation.

In the accompanying drawings:—Figure 1 is a view of a portion of a loom with my new lug strap in operative relation. Fig. 2 is a top plan view of the strap, showing a 35 picker stick in place. Fig. 3 is a longitudinal section through the strap, the parts carried by the picker stick and also the adjacent portion of the picker stick being shown. Fig. 4 is a perspective view of the removable 40 picker stick connection of the strap. Fig. 5 is a side elevation of the rock shaft connecting end of the strap, taken from an opposite side to that shown in Fig. 1. Figs. 6 and 7 are detail perspective views of the coöperating 45 parts carried by the picker stick.

Referring to the drawings, the numeral 10 designates the strap proper, which connects the picker stick 11 for operation from the rocking arm 12 of the loom, the picker 50 stick and rocking arm being indicative of any form desired to be used.

The lug strap 10 consists of a main body 13 made preferably of wood, and recessed at 14, and having the flat terminal 15, the recess 14 and the terminal 15 coöoperating with 55 the block 16 and the terminal 17, to form a

receptacle for the picker stick. The terminal 17 is provided with the elongated opening 18, while a bolt receiving opening 19 is formed in the block 16, the two bolts 20 and 21 being employed to detachably connect the block and terminal securely to the body 13. To assist in holding and protecting the edges of the parts 15 and 17, the metal plates 22 and 23 are provided. It is of course understood that the member composed of the block 16 and terminal 17 is also made of wood.

The other end of the body 13 is recessed at one side as at 24, the end being provided 70 with the curved seat 25 and the flat terminal 26, so that the block 27 and its terminal 29, which is also provided with the curved seat 28, may be removably attached in place by the two bolts 30 and 31, the metal protecting 75 plates 32 and 33 being employed also. The two leather strips 34 and 35 are held in place by the block and the bolts, so that the two curved seats 25 and 28 will be substantially lined with leather to receive the end of the 80 rocking arm 12. By this means should either removable end member of the strap split or become useless, a new one can be substituted without destroying or discarding the body 13.

The picker stick is provided with the metal clip or clamp 36, which is adjusted and held in place upon the stick by means of the bolt 37, the leather buffer 38 being held upon one face of the stick and provided with 90 the head 39, so that should the clamp become loose, the head will still prevent the buffer from falling through the opening of the strap, through which the picker-stick passes. This buffer, as shown in Fig. 7, is 95 T-shaped in plan. The wedge 40 having the driving head 41, coöperates with the clamp 36 and the buffer 38 to hold the buffer fixedly in adjusted position.

With this form of strap, the various elements due to splitting or wear can be replaced, thus producing a very useful picker stick lug strap, and also one which may be adjusted to accommodate the rocking arm and picker stick.

100 What I claim as new is:—

1. A picker stick lug strap, comprising a main body having a recess for a portion of its length to provide a flat terminal, a block mounted in the recess and having a terminal to engage the body, the recess and terminal 110 of the body and block constituting a recep-

- tacle for the picker stick, bolt members passed through the terminals of the body and block for detachably connecting the same together, said body being formed with
- 5 a further recess having a curvilinear wall, a second block having a recess provided with a curvilinear wall, means detachably securing the second block in the recess with the curvilinear walls arranged in coöperative
- 10 relation to each other to provide a substantially circular opening for receiving the rocking arm of a loom, the opening being disposed at right angles to the first named recess.
- 15 2. A picker stick lug strap, comprising a main body having a recess for a portion of its length to provide a flat terminal, a block mounted in the recess and having a terminal to engage the body, the recess and terminals
- 20 of the body and block constituting a receptacle for the picker stick, bolt members

passed through the terminals of the body and block for detachably connecting the same together, said body being formed with a further recess having a curvilinear wall, a 25 second block having a recess provided with a curvilinear wall, means detachably securing the second block in the recess with the curvilinear walls arranged in coöperative relation to each other to provide a substantially circular opening for receiving the rocking arm of a loom, the opening being disposed at right angles to the first named recess, and fibrous strips interposed between the body and last named block and extend- 30

ing within the opening.

In testimony whereof I affix my signature.

JOSEPH F. VAILLANCOURT.
